UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT STOCK COMPANY OF FRANCE.

WHEELED GUN-CARRIAGE.

1,310,882.

Specification of Letters Patent. Patented July 22, 1919.

Application filed May 15, 1917. Serial No. 168,858.

To all whom it may concern:

Be it known that I, EUGÈNE SCHNEIDER, a citizen of the Republic of France, and residing at Le Creuzot, Saône-et-Loire, France, have invented a new and useful Improvement in or Relating to Wheeled Gun-Carriages, which is fully set forth in the following specification.

This invention relates to improvements in 10 wheeled gun carriages adapted to slide on the wheeled axle for the purpose of training.

These improvements consist essentially in 15 guiding the gun carriage upon the axle by means of a box composed of two elements capable of sliding vertically relatively to each other, without relative longitudinal displacement; one element of the said box is carried by the carriage and the other by the 20 axle, and metal or other springs are interposed between the said elements of the box.

By this means the body of the carriage is 25 mounted elastically on the axle, and also in such a manner as not to interfere in any way 25 with the freedom of sliding of the entire gun carriage along the wheeled axle.

The mechanism for effecting the sliding of the carriage along the axle may be carried wholly by that element of the box that 30 slides directly on the axle. In a modification, the said mechanism may be carried in part by that element of the box that slides directly on the axle, and in part by the carriage and that element of the box that is 35 fixed to the carriage. In that arrangement, the two parts of the mechanism are connected together by a telescopic spring device whose elements are jointed by means of Cardan joints to those parts of the mechanism 40 that are to be connected to one another.

The manner in which this invention is to be performed will now be more particularly described with reference to the accompanying drawings which illustrate by way 45 of example, two practical constructions of apparatus according to this invention. In these drawings:

Figure 1 is a vertical longitudinal sectional view of one constructional form of 50 the invention;

Fig. 2 is a horizontal sectional view on the line II—II of Fig. 1;

Fig. 3 is a cross sectional view on the line III—III of Fig. 2;

Figs. 4 to 8 illustrate a second practical 55 construction of apparatus;

Fig. 4 is a vertical section;

Fig. 5 is a horizontal section on the line V—V of Fig. 4;

Fig. 6 is a vertical longitudinal section on 60 the line VI—VI of Fig. 4;

Fig. 7 is a cross section on the line VII—VII of Fig. 6;

Fig. 8 is a part section on the line VIII—VIII of Fig. 4. 65

In these various figures A is the gun carriage proper, constructed so as to be capable of sliding along the wheeled axle C. According to this invention, the guiding of the carriage A on the axle, in its sliding 70 movement along the latter, is effected by means of a box composed of two elements B, B¹, extending one inside the other in such a manner that neither can have any longitudinal movement relatively to the other, 75 but is capable of sliding vertically one inside the other. Between these two box elements there are arranged springs D which may be of metal or otherwise.

In the constructional example shown in 80 Figs. 1 to 3, the mechanism for effecting the sliding of the carriage along the axle is carried wholly by the box element B¹, excepting of course the part which serves as a bearing or abutment on the axle. In the 85 example shown, this part consists of a nut e. In this nut works the screw E journaled in the box element B¹, and having fixed on one of its ends a pinion F connected by wheel gear G—H—I to pinion J fixed on a 90 shaft K. This shaft K, as likewise the axles g, h, i of the wheels, G, H, I, are carried by the box element B¹. The axle i is formed in the prolongation of the axle h.

In actuating the shaft K by means of one 95 or other of the hand wheels k, k¹ mounted on its ends, the screw E is rotated, and consequently caused to move longitudinally in the nut e which is fixed to the axle C.

The longitudinal movement of the screw 100 E and of the box element B¹ causes the external box element B and consequently also the carriage A to move longitudinally.

In the constructional example shown in 105 Figs. 4 to 8, the box element B¹ that slides directly along the axle, carries projecting guide claws b¹ (Figs. 4—5) for the ribs b formed on the box element B that is fixed

to the carriage A. This mutual guide device $b-b^1-b^1$ prevents all longitudinal displacement of the two box elements relatively to each other. One part of the mechanism for 5 effecting the sliding of the carriage along the axle is carried by the box element B^1 ; another part of the mechanism is carried by the carriage A and the box element B fixed to the latter.

- 10 The part that serves to provide a bearing or abutment of the mechanism upon the axle is in this case constituted by a rack c . That part of the mechanism that is carried by the box element B^1 comprises a pinion L which 15 engages with the rack c and has its axle l journaled in the said box element B^1 . The axle l carries also a helical pinion M which engages with a worm N fixed on the shaft n journaled likewise in the box element B^1 .
20 The shaft n carries further, on each of its ends, a beveled pinion N^1 engaging with a pinion O whose axle o is journaled like the shaft n and the axle l in the box element B^1 .
25 The axle o carries further, the element P of a cardan joint $P-P^1$ the other element P^1 of which is carried by one of the short shafts Q^1 of a telescopic device Q^1-Q . The short shaft Q^1 has a key q^1 slideable 30 in a slot q in the short shaft Q. A spring R bears at its ends respectively against the two shafts Q^1 and Q. The short shaft Q carries at its other end, the element S^1 of a Cardan joint $S-S^1$ the other element S of 35 which is carried by the axle s journaled in a

bracket a fixed to the gun carriage A and the box element B.

The axle s carries a pinion T engaging with a pinion U whose axle u is journaled in the bracket a and carries a hand wheel V. 40

Gear N—O—T—U— and hand-operating wheel V similar to that which has been described, may be provided at each end of the shaft n .

Having now described my invention, what 45 I claim as new and desire to secure by Letters Patent is:

1. An apparatus for mounting a gun carriage sliding along a wheeled axle, wherein the guidance of the gun carriage in its sliding movement along the wheeled axle is effected by means of a box composed of two elements carried respectively by the gun carriage and the axle, and capable of sliding vertically in relation to each other without 50 relative displacement along the axle; metal or other springs being arranged between the said two elements.

2. An apparatus, as claimed in claim 1, wherein the mechanism for sliding the gun carriage along the axle is carried wholly by that element of the box that slides directly on the axle. 55

In testimony whereof I have signed this specification in the presence of two subscribing witnesses.

EUGÈNE SCHNEIDER.

Witnesses:

CHAS. P. PRESSLY,
ANDRÉ MOSTICKER.
